UNITED STATES PATENT OFFICE.

PERRY CALVIN WALLACE, OF MONTGOMERY, ALABAMA.

HINGE.

1,404,498.

Specification of Letters Patent. Patented Jan. 24, 1922.

Application filed March 25, 1921. Serial No. 455,403.

To all whom it may concern:

Be it known that I, PERRY C. WALLACE, a citizen of the United States, residing at Montgomery, in the county of Montgomery 5 and State of Alabama, have invented a new and useful Hinge, of which the following is a specification.

By way of explanation, it may be stated that when a door, window, lid or other closure is suspended by means of hinges for swinging movement, the closure, in many instances, does not fit properly with respect to the jambs. This improper fitting may result from lack of care or skill in the cutting of the gains for the hinges, or, if no gains are cut, it may result from an irregularity in the shape of the door, or from a lack of parallelism in the jambs.

Any difficulty of the sort above mentioned 20 is alluded to, the common practice is to place shims of card board, wedges of wood or the like, between the leaves of the hinge and the jamb or between the wings of the hinges and the closure. Such shims, wedges, and the like, rarely are permanent, durable and satisfactory. They lose their shape and position, fall out, or become useless otherwise, and as a result, the door sags or changes its position.

30 The foregoing being understood, it may be stated that it is the object of this invention to provide a hinge which is so constructed, that, by simply adjusting the screws which hold the hinge in place, the door may be 35 made to hang properly.

It is within the province of the disclosure to improve generally and to enhance the utility of devices of that type to which the invention appertains.

40 With the above and other objects in view, which will appear as the description proceeds, the invention resides in the combination and arrangement of parts and in the details of construction hereinafter described 45 and claimed, it being understood that, within the scope of what is claimed, changes in the precise embodiment of the invention shown can be made without departing from the spirit of the invention.

50 In the accompanying drawings:—

Figure 1 shows in elevation, a hinge constructed in accordance with the invention, the hinge being opened; Figure 2 is a sectional view, showing the hinge applied to a 55 closure and a jamb.

The numeral 1 denotes a jamb and the

numeral 2 marks a door, window, lid or other closure. The closure 2 is connected to the jamb 1 by a hinge 3 including leaves 4 which may be connected pivotally in any 60 desired way. The leaves 4 may have knuckles 5 through which a pin 6 passes, as common. Screws 7 unite the leaves 4 with the jamb 1 and with the door 2. The leaves 4 have openings 8 through which the screws 65 7 pass. The leaves 4 are provided with transverse seats or grooves 9 wherein resilient members 10, preferably in the form of strips of rubber or other resilient material, are retained, the seats 9, preferably being 70 undercut slightly, as indicated in Figure 2 in order to retain the strips 10. The strips may be cemented in or held otherwise in the seats 9. The strips or resilient members 10 project beyond the inner surface of the 75 leaves 4 and bear against the jamb 1 and the door 2. Clearly, by tightening up or advancing the screws 7, the members 10 may be compressed more or less, and in this way, the door or other closure 2 may be adjusted 80 with respect to the opening wherein it swings.

Although both leaves of the hinge are provided with the resilient members 10, but one wing can be so equipped, if desired. 85

Having thus described the invention, what is claimed is:—

1. A hinge comprising leaves, each composed of a single layer, one of said leaves being provided with a resilient member, one 90 edge of the resilient member projecting beyond all portions of said leaf, and being exposed, for compression and to afford an adjustment of said leaf when the leaf is secured in place, the opposite edge of the 95 resilient member abutting against said leaf to secure a compression of the resilient member by said leaf.

2. A device of the class described, constructed as set forth in claim 1, and further 100 characterized by the fact that said leaf is provided with a groove extended but part way therethrough, the resilient member fitting closely in the groove and being held therein by its resiliency. 105

In testimony that I claim the foregoing as my own, I have hereto affixed my signature in the presence of two witnesses.

PERRY CALVIN WALLACE.
